HANDBAG

Paul F. Franitz, 3152 N. 90th St.,
Milwaukee, Wis. 53222
Filed July 21, 1970, Ser. No. 24,053

Term of patent 14 years

Int. Cl. D3—01

U.S. Cl. D87—3

FIG. 1 is a side elevational view of a handbag embodying my new design;

FIG. 2 is a front elevational view;

FIG. 3 is a top plan view;

FIG. 4 is a bottom plan view; and

FIG. 5 is a rear elevational view thereof.

I claim:

The ornamental design for a handbag, as shown.
